FLUID PRESSURE INTENSIFYING DEVICE

Oliver J. Saari, Bronx, N. Y.

Application April 16, 1948, Serial No. 21,537

5 Claims. (Cl. 103—49)

1

This invention relates to a hydraulic pressure intensifier, and more particularly to a device for boosting the pressure in a hydraulic fluid line to give a smooth uninterrupted flow without the aid of additional pumps or motors.

The booster of the invention is easily installed in the pressure line of a pump, and by increasing the pressure permits the use of smaller ram diameters, faster advance and return speeds, and continuous high pressure for holding, deep drawing, etc. The device may be mounted in any position without altering its effectiveness.

Further advantages of the booster are that it may be used with large volume pumps, and can be used with either variable or constant delivery pumps. The device contains no bearings or packings to service, and needs no adjustments. By its design, the booster may be produced at low cost and maintained in service over long periods with no maintenance cost.

An object of the invention is to provide a hydraulic pressure intensifier having the above advantages.

Another object of the invention is to provide a booster including a pair of interlocked and self-synchronizing pistons so arranged as to provide delivery of intensified oil pressure at all times.

These and other objects of the invention will be apparent from the following specification and the accompanying drawing, in which the figure shows a preferred embodiment of the invention, partly in elevation, and partly diagrammatically.

In the drawing, the device comprises a main housing 10 encasing a pair of pistons 11 and 12 reciprocable in cylinders 11a and 12a. An annular groove 13 is provided near the left end of piston 11, and similar grooves 14a and 14b are provided near the ends of piston 12. Each piston has piston rods 15, 16 and 17, 18 extending from each of its ends and extending into cylinders 15a, 16a, 17a and 18a, respectively, these cylinders being of less diameter than cylinders 11a and 12a, and being in communication with the larger cylinders through reduced cylinder portions 20 which are dimensioned to provide for movement of the piston rods but at the same time to seal off the large cylinder portions 11a, 12a from the smaller cylinder portions 15a, 16a, etc. Cylinder 15a is connected at its closed end with cylinder 17a by a passage 22 containing two check valves 23, 24 opening only toward each other. A conduit 25 for the intensified pressure fluid is connected to conduit 22 at a point between check valves 23, 24.

Cylinders 16a and 18a are connected at their

2

closed ends by a conduit 27 and check valves 28 and 29 corresponding in position and direction of opening to those connecting cylinders 15a and 17a. Conduit 27 also communicates with intensified pressure conduit 25 at a point between check valves 28, 29.

Conduits 22 and 27 are connected to and paralleled along most of their lengths by conduits 30, 31, respectively, each containing a pair of one way check valves 32, 33 and 34, 35 spaced in a manner similar to the check valves 23, 24 and 28, 29, but operating oppositely to the latter, that is, check valves 32 and 33 permit flow of fluid only toward cylinders 15a and 17a, respectively. Check valves 34 and 35 permit flow only toward cylinders 16a and 18a, respectively. Conduits 30 and 31 are both connected at points located between their check valves with a conduit 37 which receives fluid being fed to the device by a pump or other pressure source (not shown).

Passages 40 and 41 provide communication between the ends of cylinders 11a and the corresponding ends of cylinder 12a, and these two passages both connect with fluid supply passage 37. Conduits 40 and 41 are connected to and paralleled along most of their lengths by passages 42 and 43, respectively, the two latter passages being connected with a drain conduit 44 which leads, for example, back to the fluid supply tank (not shown).

Conduits 40, 41, 42, and 43 communicate with cylinders 51 and 52 which contain movable pistons 53 and 54, respectively. The openings of passages 40, 41, 42 and 43 into cylinders 51 and 52 are spaced along the lengths of these cylinders and each of the pistons 53, 54 has four openings so positioned that piston 53 while blocking passages 40 and 43, permits flow through passages 41 and 42. In the other position of piston 53, it permits fluid flow through passages 40 and 43 and blocks passages 41 and 42. Piston 54 is similarly constructed and operable, except that, as will be explained presently, piston 54 operates out of phase with piston 53.

The right end of cylinder 51 is connected by a passage 56 with the interior of cylinder 11a near its mid point, and the left end of cylinder 51 is connected by a passage 57 with the left end of cylinder 12a at a point located a short distance from the left end of cylinder 12a. The opening of passage 56 into cylinder 11a is so positioned that the right hand end of piston 11 moves clear of the opening when the piston moves to its extreme left hand position. The left end of cylinder 52 is connected by a passage 58 with

cylinder 12a at a point located between the mid point of the cylinder and its left end and spaced still further from the left end of cylinder 12a than the point where passage 57 opens into the cylinder. The right end of cylinder 52 is connected by a passage 59 with cylinder 12a at a point slightly to the right of the mid point of cylinder 12a.

Cylinder 12a has a connection to drain at 60 located near the center of cylinder 12a in such a relation to the other connections to that cylinder that groove 14a will connect passage 59 to drain at 60 when piston 12 is in its extreme right hand position, while groove 14b will connect passage 58 to drain at 60 when piston 12 is in its extreme left hand position.

In the case of cylinder 11a, it has a connection to drain at 61 so positioned that groove 13 will connect passage 56 to drain at 61 when piston 11 is in its extreme right hand position.

In the phase of operation shown in the drawing, the pressure from the pump (not shown) entering conduit 37 passes through check valve 34 and at the same time through passage 41, thus applying pressure to the end of piston rod 16 and to the right end of piston 11, causing movement of piston 11 to the left. The pressure from the pump also passes downwardly through port 40 into the left end of cylinder 12a, and at the same time passes through port 36 to open check valve 33 and pass into cylinder 12a which also assists in moving piston rod 17 and piston 12 to the right in the drawing. Access of pressure fluid to the left surface of piston 11 is prevented by piston 53 so that the pressure on combined areas of piston 16 and the right end of piston 11 overcomes pressure tending to open valve 32, thus maintaining this valve closed and forcing piston 11 and piston rod 15 to the left and opening valve 23.

The pressure in the left end of cylinder 12a passes through conduit 57 as soon as piston 12 has moved far enough to the right to uncover the opening of passage 57 into cylinder 12a so that the pressure within cylinder 12a passing through conduit 57 passes into the left end of cylinder 51 to move piston 53 to its right-hand position as shown and to maintain it in this position. As long as piston 53 is in its right-hand position as shown, it connects the left end of cylinder 11a through the upper portion of conduit 40 and the upper portion of conduit 42 with the conduit 44 which passes to drain, thus permitting movement of piston 11 to the left. The fluid in cylinder 15a passes through check valve 23, forcing this valve open, and then passes through conduit 25 which is the conduit for the fluid under intensified pressure. Check valve 24 prevents passage of the fluid from cylinder 15a into cylinder 17a. It will be apparent that the pressure of the fluid passing from cylinder 15a to conduit 25 is intensified due to the fact that the pressure on the surfaces of piston 11 and piston rod 16 is concentrated on fluid in contact with piston rod 15, the left end of cylinder 11a being connected to drain.

The movement of piston 12 to the right under the pressure of the fluid passing through the lower portion of conduit 40 and through the lower portion of conduit 30 past check valve 33 causes an increase in the pressure in cylinder 18a since the right end of cylinder 12a is connected to drain, and the fluid in cylinder 18a is forced past check valve 29 into the intensified pressure conduit 25, check valve 28 preventing

5 movement of this fluid through passage 31. The fluid entrapped within the right-hand end of cylinder 12a during the movement of piston 12 to the right escapes through conduit 43 to the conduit 44 which connects to the drain.

As piston 12 moves to the right, it exposes first the opening of conduit 57 into cylinder 12a to shift piston 53 to the right as described above, and thereafter with further movement of piston 12 to the right, exposes the opening of conduit 58 into cylinder 12a, thereby permitting the incoming fluid pressure from passage 37 to pass from cylinder 12a through conduit 58 to the left-hand end of cylinder 52 so as to urge piston 54 to the right. This movement of piston 54 to the right cannot take place, however, until piston 12 reaches its extreme right-hand position, in which it is shown in the drawing, where it connects the right-hand end of cylinder 52 through conduit 59 and groove 14a in piston 12 to drain through passage 60. When the pressure within the right-hand end of cylinder 52 is thus released, the piston 54 is free to move to the right from the position in which it is shown in the drawing. In the right-hand position of piston 54, conduit 49 is blocked, conduit 42 is open, conduit 43 is closed, and conduit 41 is open.

Movement of piston 54 to its right-hand position closes off the flow of fluid from the pump to cylinder 12a through conduits 37 and 40 due to the fact that it blocks conduit 40, but at the same time, it connects the left-hand end of cylinder 12a through conduit 42 to the drain conduit 44. In its right-hand position, piston 54 also connects the right-hand end of cylinder 12a to the incoming fluid pressure conduit 37 since it opens conduit 41 and blocks the connection 43 of the right-hand end of cylinder 12a with drain conduit 44. The fluid pressure entering through conduit 37 then forces open check valve 35 so as to pass into the right-hand end of cylinder 18a, while at the same time the fluid pressure from conduit 37 enters the right-hand end of cylinder 12a through conduit 41. The combined pressures on the right-hand ends of piston 12 and piston rod 18, and the connecting of the left-hand end of cylinder 12a through conduit 42 to drain permits the pressure from conduit 37 to force the piston 12 to the left so as to place the fluid within cylinder 17a under intensified pressure, and to force this fluid past check valve 24 into the intensified pressure conduit 25. Check valve 23 prevents the intensified fluid pressure from passing through the upper part of passage 22 into cylinder 15a.

When piston 11 completes its leftward movement it exposes the opening of conduit 56 into the interior of cylinder 11a and permits pressure from conduit 37 through conduit 41 to pass from the interior of cylinder 11a into conduit 56 and thence into the right-hand end of cylinder 51 to urge piston 53 to its left-hand position in which it closes conduit 41, opens conduit 43, closes conduit 42, and opens conduit 40. This leftward movement of piston 53 occurs at the time when conduit 57 is connected through the left end of cylinder 12a and through conduit 42 to drain, that is, when piston 12 is not covering the lower end of conduit 57.

The opening of conduit 43 by piston 53 connects the righthand end of cylinder 11a with the drain conduit 44 and the closing of conduit 41 disconnects the righthand end of cylinder 11a from communication with the incoming pressure conduit 37. The closing of conduit 42 disconnects

the left end of cylinder 11a from communication with the drain conduit 44, while the opening of conduit 40 permits fluid pressure from conduit 37 to enter the left end of cylinder 11a. The pressure from conduit 37 also forces open check valve 32 and passes into the smaller cylinder 15a. The intensified pressure from cylinder 11a holds check valve 23 closed. Since the righthand end of cylinder 11a is connected to the drain conduit through passage 43 and pressure from pump conduit 37 is passing into both cylinder 15a and the left end of cylinder 11a, piston 11 is therefore forced to move to the right and the fluid entrapped within cylinder 16a is forced past check valve 28 under intensified pressure into the intensified pressure conduit 25, meanwhile holding valve 34 closed.

Returning now to piston 12, the leftward movement of piston 12 after movement of piston 54 to the right finally brings groove 14b into a position to connect conduit 58 with drain conduit 60, and at the same time to expose the connection of conduit 59 with the right end of cylinder 12a so as to permit the pressure from conduits 37 and 41 within the righthand end of cylinder 12a to pass through conduit 59 into the righthand end of cylinder 52 so as to urge piston 54 to its lefthand position, the fluid under pressure in the lefthand end of cylinder 52 escaping through conduit 58, along groove 14b, and out of drain conduit 60. With this occurrence, the lefthand end of cylinder 12a is again connected with the pump pressure conduit 37 and the righthand end of cylinder 12a is connected through conduit 43 with the drain conduit 44. Piston 12 then starts the movement to the right under the pressure of fluid from conduit 37 passing through conduit 40 into the left end of cylinder 12a. The fluid entrapped within cylinder 18a is forced past check valve 29 under intensified pressure into conduit 25.

As piston 12 moves to the right it first passes the opening of conduit 51 into cylinder 12a and permits part of the fluid within the left end of cylinder 12a to pass into the left end of cylinder 51 to shift piston 53 to its righthand position as is shown in the drawing. This movement to the right of piston 53 cannot take place of course until piston 11 has reached its extreme position of movement to the right in which it connects conduit 56 through groove 13 with the drain conduit 61 so as to relieve pressure within the righthand end of cylinder 51. The movement of piston 53 to the right then permits pressure from conduit 37 to pass into the right end of cylinder 11a, and permits fluid in the left end of cylinder 11a to pass out through the upper portions of conduit 40 and 42 to the drain conduit 44. The fluid entrapped within cylinder 15a is placed under increased pressure and forced past check valve 23 under intensified pressure conduit 25.

It will thus be clear from the above description that the mode of operation described continues over and over again as long as the pressure is supplied to conduit 37.

With respect to the relative positioning of drain duct 60 and the openings of ducts 58 and 59 into cylinder 12a, the positioning is such that when piston 12 is in its extreme righthand position, duct 59 is connected to duct 60 and the left end of piston 12 exposes opening of conduit 58 into cylinder 12a. When piston 12 is in its extreme lefthand position, conduit 58 is in communication by means of groove 14b with drain duct 60 and the righthand end of piston 12 exposes the opening of

duct 59 into cylinder 12a so as to permit communication between duct 59 and the lower end of conduit 41. When the piston 12 is in its extreme lefthand position, there is, however, no communication between conduit 59 and drain duct 60.

With respect to the positioning of drain duct 61 and the opening of conduit 56 into cylinder 11a, the drain duct 61 is offset to the left out of line with the opening into conduit 56 so that when piston 11 is in its extreme lefthand position the drain conduit 61 is closed and conduit 56 is in communication through the interior of cylinder 11a with the upper end of conduit 41. When the piston 11 is in its extreme righthand position, the opening of duct 56 into the interior of cylinder 11a communicates with groove 13 which also communicates with drain conduit 61.

It will be apparent that the speed of the pistons 11 and 12 is governed by the capacity of the pump supplying fluid to conduit 37, so that the greater the volume of fluid supply, the greater the speed of the pistons. The spring pressed ball check valves 23, 24, 28, and 29 reduce the pulsation at the stroke reversing intervals to an absolute minimum by preventing any momentary backflow of the intensified pressure oil.

One or more spring loaded detents 70' are used with each of the two piston valves 53 and 54 so as to retain these piston valves in each of their two positions except when the pressure in one or the other ends of the cylinders 51, 52 is sufficient to move the respective piston to its other position. These detents also serve the function of holding the valve pistons 53, 54 in their respective positions regardless of the orientation of the mounting of the pressure intensifier itself. The detents could of course be located in the housing or body 10 to cooperate with depressions in the pistons 53, 54. Suitable projections (not shown) on the ends of valve pistons 53 and 54 may be provided to limit their movement in each direction.

It should also be apparent that the amount of intensification of the pressure is a function of the differential ratio between the surface of the ends of pistons 11 and 12 and the surface of the surface area of the ends of each of the piston rods 15, 16, 17, 18. The volumetric output of the hydraulic intensifier is of course inversely proportional to the pressure ratio so that, for example, if the pressure is doubled, the volumetric output is halved, or if the pressure is tripled, the volumetric output decreases to a third of the original volume.

It is obvious that the device which I have described is capable of numerous variations without departing from the inventive concept. For example, the reciprocating valve pistons 53 and 54 could be replaced by other types of valves, such as fluid operated oscillating valves. The ball check valves which reduce pulsation at the stroke reversing intervals to an absolute minimum by preventing momentary back flow of the fluid under intensified pressure could be replaced by other types of similarly operating check valves. The shape of the main pistons could also be varied so long as each piston has at least two separate fluid pressure areas on each end so that the separate areas on the side of a piston in the direction of movement of the piston can be connected one to the intensified pressure outlet and one to drain. The annular grooves about each main piston could be replaced by passages through the piston, although this might necessitate maintaining the pistons against rotation.

The form of the invention which I have de-

scribed is but a preferred embodiment, and is not to be considered as limiting the invention to the specific embodiment shown. It is my intention to cover by my patent all variations of the invention falling within the scope of the claims and outside the prior art.

I claim:

1. A fluid pressure intensifying device comprising a fluid supply inlet, an outlet for fluid under intensified pressure, a drain outlet, two reciprocable pistons each having two sides and each side being divided into at least two separate fluid contact areas, first conduit means for connecting said inlet with all of said fluid contact areas, second conduit means for connecting one fluid contact area of each side of each piston to said drain outlet, valve means controlling said second conduit means and at least some of said first conduit means, said valve means having positions for completing the connection of said fluid supply inlet to both areas of one side of each piston to move said piston in a direction away from that side, while blocking one area of each of the other piston sides from communication with said inlet and connecting said blocked area with said drain outlet, third conduit means connecting the remaining side of each piston with said intensified pressure outlet, and connection reversing means operable by said pistons to shift said valve means to reverse said connections as said pistons approach the limits of their movement in each direction, thereby reversing the direction of movement of said pistons, said valve means comprising two fluid operated valves, each having two positions, first and second cylinders in which said pistons reciprocate, connections to drain positioned in the side wall of each cylinder, said pistons having passages which communicate with one of said drain connections during a portion of the piston movement, said connection reversing means including first and second valve operating fluid passageways connecting the first valve with both end portions of the first cylinder and third and fourth valve operating fluid passageways connecting the second valve with one end portion of each cylinder, the proportioning of said pistons, the positioning of said passages and the positioning of the openings of said passageways into said cylinders being so related that in one extreme position of movement of said first piston, the first of the passageways to said first valve is connected to a drain connection by a passage in said piston while the second passageway to said first valve is in communication through a first end of said cylinder with the piston moving fluid from said inlet, said first piston in its opposite extreme position putting said first passageway into communication with the other end of said first cylinder for receiving fluid therefrom and putting said second passageway in communication with a drain connection through a passage in said first piston, said second piston in one extreme position of movement connecting said third passageway with a drain connection and in its other extreme position putting said third passageway in communication with one end of said cylinder to receive fluid therefrom, said fourth passageway being connected to said first cylinder at a point positioned between the end of the cylinder and the opening of the second passageway into the cylinder to receive fluid from that end of the cylinder during the major portion of the movement of said first piston in both directions.

2. A device as set forth in claim 1, said fluid operated valves being piston valves, valve cylinders in which said valve pistons reciprocate, said first and second passageways being connected to opposite ends of the cylinder of said first piston valve, and said third and fourth passageways being connected to opposite ends of the cylinder of said second valve.

3. A fluid pressure intensifying device comprising a fluid supply inlet, an outlet for fluid under intensified pressure, an outlet to drain, a pair of main cylinders having enlarged central portions and reduced end portions, a piston reciprocably mounted in each cylinder, each piston having an enlarged central portion and a reduced end portion slidable in the corresponding cylinder portions, first and second conduits connecting one reduced end portion of one cylinder with a reduced end portion of the other cylinder, third and fourth conduits connecting the other reduced end portions of the two cylinders, a pair of spaced check valves in each of said first and fourth conduits, each check valve opening only toward the other check valve in the same conduit, said check valves permitting flow only in a direction away from the reduced cylinder portions to which said first and fourth conduits connect, a pair of spaced check valves in each of said second and third conduits, each of said last mentioned check valves opening only away from the other check valve in the same conduit, said last mentioned check valves permitting flow only in a direction toward the reduced cylinder portions to which said second and third conduits connect, a connection from said fluid supply inlet to said second and third conduits at points located between the check valves in each conduit, a connection from said intensified pressure outlet to said first and fourth conduits at points located between the check valves in each conduit, fifth and sixth conduits paralleling said first and second conduits and connecting the ends of the enlarged portions of the two cylinders which correspond to the reduced ends connected by the first and second conduits, seventh and eighth conduits similarly connecting the other ends of the enlarged cylinder portions, first and second valve cylinders each intersecting said fifth, sixth, seventh and eighth conduits at spaced positions, a first connection from one end of the first valve cylinder to the interior of the enlarged portion of the first main cylinder at a point located on one side of the center of the cylinder so as to be uncovered by the piston in that cylinder during the final portion of the movement of that piston toward the end of the cylinder farther removed from said connection, a second connection from the other end of said first valve cylinder to the interior of the enlarged portion of said first main cylinder at a point positioned similarly to said first connection but on the opposite side of the mid point of said cylinder, a third connection from one end of the second valve cylinder to the interior of the enlarged portion of said first main cylinder at a point positioned between said second connection and the end of the main cylinder nearer the second connection, a fourth connection between the other end of said second valve cylinder and the interior of the enlarged portion of the second main cylinder at a point positioned to one side of the mid point of the cylinder so to be uncovered by the piston in said cylinder during the final portion of its movement toward the end of the cylinder farther removed from said fourth connection, means carried by said first piston for connecting said first

connection to drain at one end piston position and for connecting the second connection to drain in its other end position, means carried by said second piston for connecting said fourth connection to drain when said second piston is in its end position of movement in the direction of the end of the cylinder nearer said connection, a connection from said fluid supply inlet to said fifth and eighth conduits at points located between the intersections of said conduits with said valve cylinders, a connection to drain communicating with said sixth and seventh conduits at points located between the intersections of said conduits and said valve cylinders, and a valve piston in each of said valve cylinders, each of said valve pistons having two positions and having ports located so that each piston blocks said first and third conduits and completes said second and fourth conduits in one position, and blocks said second and fourth conduits and completes said first and third conduits in the other position.

10

15

20

4. A fluid pressure intensifying device as set forth in claim 3, said means carried by said main pistons comprising annular grooves about the peripheries of said pistons.

5. A fluid pressure intensifying device as set forth in claim 3, and spring pressed detent means yieldably retaining said valve pistons in each of their positions.
